[57] **CLAIM**

The ornamental design for a handle end of the carrying case, as shown and described.

DESCRIPTION

FIG. 1 is an isometric view of a handle end of the carrying case showing the new design;

FIG. 2 is a bottom plan view thereof;

FIG. 3 is a front elevational view thereof;

FIG. 4 is a top plan view thereof; and,

FIG. 5 is a side elevational view thereof, the opposite side being a mirror image.

The broken lines in FIGS. 1-5 are for illustrative purposes only and form no part of the claimed design.

1 Claim, 2 Drawing Sheets

FIG. 1

FIG. 2

FIG. 3

FIG. 5 FIG. 4
